No. 36,695.

Patented December 22, 1903.

UNITED STATES PATENT OFFICE.

GUSTAVE F. KOLB, OF NEW YORK, N. Y.

DESIGN FOR A TRAY.

SPECIFICATION forming part of Design No. 36,695, dated December 22, 1903.

Application filed November 27, 1903. Serial No. 182,915. Term of patent 7 years.

To all whom it may concern:

Be it known that I, GUSTAVE F. KOLB, a citizen of the United States, residing at New York city, (Manhattan,) county and State of New York, have invented a new, original, and ornamental Design for Trays, reference being had to the accompanying drawing, which is a plan of a tray, showing my new design.

What I claim is—

The ornamental design for a tray, substantially as herein shown.

GUSTAVE F. KOLB.
